Thomas Remond
ATTORNEY

UNITED STATES PATENT OFFICE

CLAUDIUS NIELSEN, OF DETROIT, MICHIGAN

ICE CASING FOR REFRIGERATORS

Application filed June 10, 1926. Serial No. 114,886.

My invention relates to a new and useful improvement in a casing for the reception of ice in refrigerators, and has for its object the provision of a device of this class which will effect an economy in the use of ice in refrigerators without materially lessening the refrigerating efficiency of the refrigerator.

Another object of the invention is the provision of a device of this class which will be simple in structure, economical of manufacture and highly efficient in use.

Another object of the invention is the provision of a casing of this class of a formation to effect the air circulation in the refrigerator in such a manner as to maintain the refrigerator at substantially its normal refrigerating efficiency, while at the same time retarding the melting of the ice used therewith.

Other objects will appear hereinafter.

20 The invention consists in the combination and arrangement of parts hereinafter described and claimed.

The invention will be best understood by a reference to the accompanying drawings which form a part of this specification and in which.

Fig. 1 is a fragmentary front elevational view of the ice compartment of a refrigerator showing the invention applied.

30 Fig. 2 is a fragmentary sectional view taken on substantially line 2—2 of Fig. 1.

Fig. 3 is a perspective view of the invention in a form for mounting in the compartment of a refrigerator.

35 Fig. 4 is a sectional view similar to Fig. 2 of a modified form showing the invention permanently built into a refrigerator.

The invention is adapted either for mounting in a refrigerator or for building permanently in a refrigerator and in the preferred forms I have shown a refrigerator 7 with the ice compartment 8 and a door 9 for the compartment. The invention comprises a casing which is preferably made from metal and embodies a side wall 10, a rear wall 11 and a side wall 12. The upper edges of the side walls 10 and 12 and the rear wall 11 are provided with the inwardly projecting flanges 10', 12' and 11' respectively, to which is suitably secured, by soldering, welding, or in any

other manner, a top 13. The side walls and rear walls are provided with ventilating openings 14 formed by punching the shield tongues 15 therefrom, these tongues serving as shields for preventing access to the openings 14 formed above. A door 16 is hingedly mounted on the wall 12 and serves as a closure for the forward end of the casing. Swingably mounted on the top 13 is a flap comprising the portions 17 and 18, the flap 17 being adapted, as shown in Fig. 3, for folding downwardly so as to close the crevice between the upper edge of the door 16 and the under surface of the top 13. A similar flap comprising the portions 22 and 23 is mounted on the side wall 10 for closing the crevice between the edge of the wall 10 and the inner surface of the door 16.

As shown in Fig. 2 the lower edge of the opening 19 of the compartment is positioned above the base 20 of the ice chamber and it will be noted in Fig. 3 that the walls 10 and 12 project below the lower edge of the door 16, so that when the casing is mounted in the ice chamber or compartment 8 the door 16 may be readily opened. When the device is mounted in the ice chamber or compartment 8 in the manner shown in Fig. 1 and Fig. 2 the ice 21 is positioned in the casing, and it will be noted that the upper surface of the ice 21 is spaced from the under surface of the top 13, this being preferable for most efficient results.

Tests with recording thermometers have proven that the use of the device described results in considerable saving in ice necessary for use in a refrigerator without lessening the efficiency of the refrigerator for refrigerating purposes, the temperature being substantially the same in a refrigerator in which applicant's device is used and in a refrigerator of the same kind in which applicant's device is not used. But in the refrigerator in which applicant's device is used a considerable saving of ice is effected as the ice does not melt so rapidly. It is believed that the device renders the refrigerator most efficient because of cooling in substantially the same degree with a less melting of ice, and it is thought that this increase in efficiency results from the

circulation brought about by applicant's device.

In Fig. 4 I have shown the device mounted permanently in a refrigerator 7' having the ice chamber 8' and provided with the door 9' for the ice chamber 8'. The device is constructed substantially as described for the preferred form, having the rear wall 11", the door 16', the top 13', and the openings 14' with the shields 15'. The device is shown as mounted on the top 24 of the refrigerator.

It will be noted that the side and rear walls as well as the top wall of the device are in spaced relation to the inner surface of the compartment or chamber 8 and it is believed that greater efficiency results when the device is so positioned.

While I have illustrated and described the preferred form of structure, I do not wish to limit myself to the precise form of structure shown, but desire to avail myself of such variations and modifications as may come within the scope of the appended claims.

Having thus described my invention what I claim as new and desire to secure by Letters Patent is:

1. An ice casing of the class described comprising a top wall, a rear wall and side walls, said rear wall and said side walls having vent openings formed therein; and means associated with each of said openings for deflecting downwardly air passing therethrough from the inside thereof.
2. A device of the class described comprising metallic side and rear walls adapted for mounting in the chamber of a refrigerator, a top wall carried by said side and rear walls, said walls being in spaced relation to the inner surface of said chamber, said side and rear walls having vent openings formed therein for permitting the flow of air outwardly from the interior of said casing; deflecting members mounted on the outer surface of said casing for deflecting downwardly air passing outwardly from said casing through said openings; a closure mounted on said side walls; means for closing the crevice between the edges of said closure, and said top wall and said side wall.
3. In testimony whereof I have signed the foregoing.

CLAUDIUS NIELSEN.
